Frateri & Pfeiffer
ATTORNEY

UNITED STATES PATENT OFFICE.

HELEN KANDERS, OF NEW YORK, N. Y.

SOUND AMPLIFIER.

Application filed April 7, 1925. Serial No. 21,316.

This invention relates to sound directors such as the amplifiers for broadcasting sets, phonographs, and the like, the purpose of my improvement being to provide a sound 5 issuing structure comprehending a reflector for sound waves which has the attribute of nullifying the inherent vibrational creating characteristics of the horn, and of permitting the issuance of the natural tones which 10 have been transmitted to the amplifier without the interference of foreign dissonance.

This application is a continuation in part of my applications, Serial No. 623,874, filed March 9, 1923, and Serial No. 690,374, filed

15 February 4, 1924.

In loud speakers, such as horns and other amplifiers, conditions are present that impair the purity of directed tone.

The inherent or dominant note of the horn 20 is set into sympathetic vibrations each time this specific note appears in the varying pitch of the directed voice or other sound. The duration and strength of these sympathetic vibrations are increased with each 25 recurrence, and the prolonged coexistence of disharmonies, viz: the horn's own note against the changing pitch of the voice, causes the notorious clash and impurity of transmitted sound.

30 Another defect is that in horns of usual construction two different degrees of speed of vibrations are simultaneously existent, which also results in causing a sort of clash. The vibrations of the directed tone are in 35 a forward direction and of uniform speed while the sympathetic vibrations in the amplifier slow down or are accelerated according to the number of times the dominant note of the material is roused.

40 I have demonstrated with several models, that the dominant note of the loud speaker can be eliminated and the voice transmitted with absolute purity. This is accomplished by providing a reflector of conic section, 45 (whether parabolic, elliptic, or of other contour) connected with a sound conduit. The front part of this sound conduit is continued into the reflector so that the tone should strike the opposite wall of the reflector at 50 a right angle or as near to that as possible, so as to prevent any part of the tone from passing out of the loud speaker without being reflected.

55 As the distance from the mouth of the sound conduit to the reflecting wall is negligible, the reflected tone issues co-incidentally

with its delivery from the sound conduit, and is of great purity as each successive tone, due to the forcefulness of its reflection, absorbs and thereby eliminates eventual 60 sympathetic vibrations in the material.

For the same reasons there is also only one degree of vibrational speed.

Another feature of my device is that it amplifies the transmitted sound in two ways 65 instead of one (by the length of the sound conduit and by reflection in the bell) and that therefore a comparatively small sized device can compete in tone volume with the largest horn. 70

Other features and advantages of my invention will hereinafter appear.

In the drawing:

Figure 1 is a side sectional elevation of my improved loud speaker, and

Fig. 2 is a top plan view thereof.

In said figures let 1 indicate a sound conduit, which is to convey sound waves that are produced by any well known means, as through the medium of a sound unit, 2. 75 80

This sound conduit is shown as extended vertically for a portion of its length, gradually increasing in cross-sectional diameter, and is given a return bend 3 which terminates in an open mouth 4. This mouth 4 is 85 shown as communicating with the reflector 5, at one side thereof, and at a point just adjacent the focus of said reflector. As shown, the mouth portion is entered through the side of the reflector 5, the forward portion 90 9 of said sound conduit protruding into the reflector interior to prevent the direct issuance of sound waves.

Since the longitudinal axis through the reflector is in a horizontal plane, in consequence the emitted sound from the mouth 4 of the horn is directed toward that side of the reflector opposite said mouth, and as the mouth 4 is located just adjacent the focus of the reflector, full reflective value is achieved 100 105 for the amplified sound. To aid in this effect the forward wall portion 9 of the sound conduit terminal extends into and lies part way across the interior area of the reflector, thereby preventing the direct issuance to the outside atmosphere of sound waves emitted from the sound conduit. As the effect of forward wall portion 9 lying across a part of the reflector interior is to obstruct the direct issuance from the reflector of sound waves entering it through the sound conduit, it follows that said wall 110

portion functions in the manner of a barrier or deflector, serving to direct the thus obstructed sound waves to the reflector at a point opposite the entrance to the sound conduit adjacent the reflector focus, to thereby achieve the desired reflective values.

Variations within the spirit and scope of my invention are equally comprehended by the foregoing disclosure.

10. I claim:

1. A sound amplifier comprising a reflector of conic section and a sound conduit communicating with the reflector at one side thereof in directional relation to the curved 15 surface of said reflector at its opposite side, and transversely across the focal axis of said reflector.

2. A sound amplifier comprising a reflector of conic section and a sound conduit 20 communicating with the reflector at one side thereof, at a point just adjacent to its focus, and in directional relation to the curved surface of said reflector at its opposite side, and transversely across the focal axis of 25 said reflector.

3. A sound amplifier comprising a reflector of conic section and a sound conduit having means communicating with the reflector at the side thereof and at a point just 30 adjacent its focus, the axis of said communicating means being perpendicular to the

longitudinal axis of the reflector, and a barrier extending from said sound conduit part way into said reflector.

4. An amplifier comprising a sound conduit and a reflector of conic section, the mouth of the sound conduit communicating with the reflector through the side thereof, and the forward portion only of the sound conduit, of segmental contour in cross-section, projecting part way into the reflector.

5. An amplifier comprising a sound conduit and a reflector of conic section, the mouth of the sound conduit communicating with the reflector through the side thereof, and the forward portion only of the sound conduit projecting part way into the reflector, in spaced relation to the reflector surface.

6. A horn of the character described comprising a body portion having a throat and a bell, said throat opening into said bell at a point forwardly of the inner end of the bell.

7. A semi-reflex horn comprising a body portion having a throat and bell, said throat opening into said bell at one side thereof and at a point forwardly of the inner end thereof.

Executed this 6th day of April, 1925.

HELEN KANDERS.
